DESIGN.

J. CHRISTIE.

CARPET.

No. 18,308.

Patented May 15, 1888.

UNITED STATES PATENT OFFICE.

JOHN CHRISTIE, OF HALIFAX, ENGLAND, ASSIGNOR TO JOHN CROSSLEY & SONS, OF NEW YORK, N. Y., AND LONDON, ENGLAND.

DESIGN FOR A CARPET.

SPECIFICATION forming part of Design No. 18,308, dated May 15, 1888.

Application filed February 25, 1888. Serial No. 265,309. Term of patent 3½ years.

To all whom it may concern:

Be it known that I, JOHN CHRISTIE, of Halifax, England, have invented a certain new and original Design for Carpets; and I do hereby declare the following to be a full, clear, and exact description of the same, such as will enable others skilled in the art to which it appertains to make and use the design, reference being had to the accompanying photograph, which forms a part of this specification.

My invention relates to a design for carpet-borders; and I do hereby declare that the photographic illustration accompanying this specification is and conveys to one skilled in the art of carpet-weaving a defined and full description of my invention, that is sufficient to enable any one skilled in the art of carpet-weaving to use my invention.

In the photographic illustration, D represents the border proper. At what would be 20 the inner side of this border there are shown sunflowers treated conventionally, the petals of which flowers overlap each other and produce a broken or irregular effect of outline. The outer edge of the border discloses branches 25 and foliage running outward and working over a background of Japanese ornament.

I claim—

The design for a carpet-border, as shown in the photographic illustration accompanying 30 this specification.

JOHN CHRISTIE.
